COMBINATION CHAIR AND LADDER

Filed May 11, 1928

INVENTOR.

Martin N. Johnson
BY Walter N. Haskell,

his ATTORNEY.

UNITED STATES PATENT OFFICE.

MARTIN N. JOHNSON, OF MOLINE, ILLINOIS.

COMBINATION CHAIR AND LADDER.

Application filed May 11, 1928. Serial No. 276,838.

My invention has reference to a combined chair and ladder, and is more specially designed for use in connection with some of the occupations of the kitchen, such as preparing vegetables, washing dishes and the like, and for ironing clothes. The device is made chiefly of metal, is strong and durable, and can be produced at a relatively low cost. It is readily convertible into a small step-ladder, for use in washing windows, hanging curtains and the like, or for doing other work at a height from the floor which is ordinarily out of reach. In its ordinary use as a chair the device is made of more than the usual height of a chair, so that it is convenient for use at a sink or table, in connection with which the usual chair is not of a comfortable height.

In the drawings:

Fig. 1 shows the invention in perspective, when in use as a chair.
 Fig. 2 shows the same in vertical section.
 Fig. 3 is a side elevation thereof, in use as a step ladder.
 The invention comprises a frame, including rear legs 1 and front legs 2, of angle-plate formation, united at the sides by braces 3 and 4, and at the rear by cross-bars 5 and 6. Said braces and bars are of channel-plate construction, with the openings thereof inwardly, and in the front ends of the braces 4 is a step 7, connected with the legs 2 by brackets 8. Hinged to the legs 1, as at *a* is a seat 9, formed of sheet metal, with a downwardly turned flange at its edges which encloses the upper part of the frame, when used as a chair. A back 12 is connected with the sides of the seat by a pair of braces 13, having a pivotal connection with both the back and seat. The lower ends of the side-pieces of the back are held releasably in place by keepers 14 fixed on the bar 5 near the ends thereof. The lower part of the back is foldably connected with the frame by means of rods 16, which fold upwardly against the back of the frame when the device is in use as a chair.

For use as a ladder the seat is tipped rearwardly as shown in Fig. 3, the outer part of the seat being supported on the upper part of the back 12, the side-pieces of the back being provided with pins 17 for connection with snaps 18 in the seat. The reversal of

the position of the seat makes it possible to make use of the step 7, as well as of a step 15 supported at its ends in the braces 3, and a top step 19 supported in upper channel-plates 20 of the frame. It is thereby possible to mount to the step 19 and stand thereon for purposes before mentioned. The seats 15 and 19 are also secured to the braces at their ends so as to form cross-braces, and the bars 20 at the top of the frame are sufficiently rigid to provide an additional support for one of the feet of the user of the ladder to steady the position on the upper step.

In its inverted position the seat 10 provides a support for a pail or other article, in use by the person using the ladder, this support being of a tray formation, protecting the floor beneath from water which might drip from the pail or cleaning cloths.

The lower ends of the legs 1 and 2 are preferably formed with feet 22 of non-abrasive material, and the lower ends of the side-pieces 75 of the back 12 are fitted with rubber tips 23.

The device is of suitable height to form a half-high-chair, and can be used as such by children. The steps 7, 15, and 19 are shown as being formed of wood or other solid material, the other parts of the chair being formed entirely of metal, and metal steps can be substituted for the ones shown, if desired.

What I claim, and desire to secure by Letters Patent, is:

1. A device of the class described, comprising a frame, a series of steps in one side thereof, a seat hinged to said frame, and movable away from the steps into an inverted position, a back for said seat and braces pivotally connecting the back and seat, braces connecting the back foldably with said frame, and retaining means for the lower end of the back when in use as a back, said back being in a substantially vertical position at all times.

2. A device of the class described, comprising a frame, a plurality of steps in one of its sides, a seat hinged to said frame, and invertible into a support at one side thereof, out of the way of said steps, and an auxiliary frame, foldably connected with said first-named frame and seat, forming a back for the seat when used as a seat, and a support therefor, when in an inverted position.

3. In a device of the class described, a

frame consisting of angle-plate legs and channel-plate braces therefor, two or more steps held at their ends in said braces, a sheet-metal seat hinged to said frame, and 5 provided with a flange normally enclosing the top of said frame, a back having a swingable connection with said seat, and forming

a support therefor when the seat is turned outwardly, cooperating locking means on said back and seat, and means on said frame 10 for retaining the lower end of the back when in its normal position.

In testimony whereof I affix my signature.
MARTIN N. JOHNSON.
